UNITED STATES PATENT OFFICE.

POVL HARTMANN, OF BROOKLYN, NEW YORK, ASSIGNOR, BY MESNE ASSIGNMENTS, TO ECONOMY FUSE & MANUFACTURING COMPANY, OF CHICAGO, ILLINOIS, A CORPORATION OF NEW YORK.

INCLOSED SAFETY SWITCH.

Application filed May 10, 1921. Serial No. 468,283.

To all whom it may concern:

Be it known that I, POVL HARTMANN, a subject of Great Britain, residing in the borough of Brooklyn, of the city of New York, in the State of New York, have invented certain new and useful Improvements in Inclosed Safety Switches, of which the following is a specification, reference being had to the accompanying drawings, forming a part hereof.

This invention relates to an improved inclosed safety switch which is characterized by simplicity, cheapness, ease of assembling and adaptability to a wide variety of uses.

More particularly, the invention is concerned with a switch of the character described in which the switch fuses may be housed in a simple box of stamped metal and the fuse compartment inclosed by a door which cannot be opened while the switch is closed. The operative relation between the switch and the door for the fuse compartment is carried further so that the switch cannot be closed while the door is open.

Another feature of the invention has to do with the construction of the switch box and its cover and the devices for securing the cover to the box. These devices in the preferred embodiment are so related to the door for the fuse compartment that the cover may not be removed from the box until the door for the fuse compartment is opened. This insures that the cover for the box may not be removed until the switch is open since one of the characteristics of the entire structure is that the door for the fuse compartment may not be opened except when the switch is open.

Still other locking devices of various types are associated with the switch, these locks being of a positive character and are manipulated by hand, so as to meet a variety of conditions and enable the user to secure the parts against surreptitious manipulation. One of these locks, for instance, enables the door for the fuse compartment to be positively secured; another enables the switch to be positively locked in open position, while still another enables the switch to be locked in open position and the door for the fuse compartment to be locked in closed position. The improved structure may include further a hand-operated latch mounted within the box and so disposed

with relation to the switch that the switch may be latched in open position and the cover subsequently secured on the box so as to prevent surreptitious release of the latch.

Other features of the invention are concerned with the construction of the switch, with means for adapting the entire structure to a three-wire system, and with a quick break device which may be associated with the switch for the usual purpose.

These and other objects will all be elaborated on in connection with the detailed description of the particular means illustrated in the accompanying drawings for carrying them out. In the drawings

Figure 1 is a view in plan of the improved inclosed safety switch, the cover being broken away to show the relation of parts within the box.

Figure 2 is a view, in side elevation of the box with the cover in place and the door to the fuse compartment closed.

Figure 3 is a view of a fragment of the box shown in Figure 1 and showing the door to the fuse compartment open and the switch positively locked in open position.

Figure 4 is a view in transverse section taken on the plane indicated by the line 4-4 of Figure 3 and looking in the direction of the arrows.

Figure 5 is a fragmentary detail view showing the relation of the latch within the box to the switch.

Figure 6 is a schematic view in plan showing the relation of the insulating bases for clips in a three-wire system as mounted within the improved box.

Before describing the special uses of the improved inclosed safety switch and the improvements in the parts incorporated therein, the elements and their relation will be pointed out.

The box *a* of generally rectangular outline is provided with a cover *b*, one end of which may have stamped and formed therewith lugs *b'* adapted to engage slots in the box *a* for the purpose of holding the parts together except when disengaged by relative longitudinal movement therebetween. The cover *b* has stamped and formed adjacent one of its side edges a lug *b''* with which co-operates a swinging detent *c* pivoted, as at *c'*, on the box *a* and formed with a lug *c''* to hold the cover on the box and receive

a positive lock therefor when desired. From Figure 2 it will be seen that the lug c^2 overlies the lug b^2 when the parts are aligned.

The cover b has stamped out of its top an opening to afford access to the fuse compartment which lies thereunder. This opening may be closed by a door d hinged to the cover, as at d' , and adapted to swing open to afford access to the fuse compartment. The door d is stamped and formed with a depending flange d^2 which carries a lug d^3 which, when the door is closed, lies in proximity to a lug c^2 stamped and formed on the detent c , as shown most clearly in Figure 2. The two lugs c^2 , d^3 may be engaged by a positive lock to hold the door d closed. At all events it will be evident that the relation of the lugs c^2 and d^3 when the door d is closed is such that the detent c may not swing about its pivot c' until the door d is opened. The effect of this is to prevent the lug c^2 from being disengaged from the lug b^2 and the cover b removed until the door d is opened. The reason for this will appear later.

The cover b has journaled therein a rock shaft e for the switch. This rock shaft e , when the door is closed, passes through an opening d^4 stamped out of the flange d^2 , and when the parts are in this relation the shaft e may be rocked freely to open or close the switch. The flange d^2 has stamped out of it a curved slot, indicated by dotted lines at d^5 in Figure 3. This slot communicates with the opening d^4 and is curved about the hinge joint d' . The width of the slot d^5 is less than the diameter of the rock shaft e at the point where it passes through the flange d^2 . The rock shaft e , at the point where it passes through the flange d^2 , is formed with tangential slots at opposite sides which are of such depth that the diameter of the shaft is reduced to slightly less than the width of the slot d^5 . These tangential slots are indicated by dotted lines at e' in Figure 3.

On the outer end of the shaft e is an operating handle e^2 which may or may not include a quick-break device. In the preferred form such a device is included. It consists of a short lever arm f keyed or otherwise secured to the shaft e and terminating in a spring seat f' . The handle e^2 is supported loosely on the shaft e and is extended beyond the shaft to form a lever arm e^3 which terminates in a spring seat e^4 . The spring seats f' , e^4 are alined and receive between them a suitable spring g . Operation of the handle e^2 serves to compress the spring g and the energy stored therein is impressed on the rock shaft e and serves to give a quick-break to the switch.

The shaft e within the box a is squared, as at e^5 , and supports an insulating sleeve h to which are secured releasably knife

blades i , i' , as by set screws k . The blades i , i' , when the switch is closed, span clips l , l' , and l^2 , l^3 , respectively. The clips l , l' may be connected to the mains while the clips l^2 , l^3 may be connected to clips m , m' , 70 respectively, for suitable fuses n . The other fuse clips o , o' , may be connected to the circuit to be supplied.

The rock shaft e may have co-operating therewith at a point within the box a pivoted latch p supported conveniently on the inner side wall of the box. This latch is stamped with a large opening p' , as indicated in Figure 5, so that when the shaft e rests within this opening, free rotation may be effected. The opening p' , however, terminates in a slot p^2 of less width than the diameter of the shaft e at the point at which it passes through the latch p . The shaft is formed at opposite sides with tangential slots e^6 by which the shaft at this point is reduced to a diameter slightly less than the width of the slot p^2 . In this way, the latch p may be swung until the shaft e at the point at which it is reduced by the slots e^6 90 rests within the reduced slot p^2 . With the parts in that relation the shaft e may not be oscillated.

A further feature of the invention is concerned with the provision of insulating bases, indicated at q , q' , which carry, as self-contained units, all of the clips and connections, respectively, by which the current is led from one of the main wires through a switch blade and through a fuse 100 to the circuit power to be fed. One such insulating base q , for instance, has mounted thereon the clips l , l' , for the knife blade i and the fuse clips m , o for one of the fuses n . This base q is secured to the bottom 105 of the box a by means of screws q^2 , q^3 passing through the base and threaded throughout the bottom of the box. By providing in the bottom of the box a series of holes for such retaining screws it is possible to secure thereto either two bases, such as q , q' , as shown in Figure 4, for a two-wire system, or three bases, such as q , q' , Q , as indicated diagrammatically in Figure 6, for a three-wire system.

Having described in greater part the structural features of the improved inclosed safety switch and the relation of the elements thereof, some indication of the possible uses and adaptability will be given. When the cover d of the fuse compartment is closed the rock shaft e may be oscillated either to engage or disengage the knife blades i , i' from their respective clips l , l' and l^2 , l^3 . When these blades i , i' , are disengaged from their clips, they extend up into an enlargement b^3 formed in the top of the cover b . At this time the shaft e passes through the opening d^4 in the depending flange d^2 . The lug d^3 lies over 130

the lug c^3 and the lug c^2 lies over the lug b^2 . If a positive lock is now engaged with the lugs c^3, d^3 it is evident, of course, that the door d may not be swung open. It is also evident that the detent c cannot be moved, so the cover b cannot be moved by reason of the engagement of the lug c^2 with the lug b^2 . On the other hand, if desired, the positive lock might be engaged with the lugs b^2, c^2 and not with the lugs c^3, d^3 . In this case the cover b could not be removed but the door d might be opened to give access to the fuses n . The tangential slots e' in the rock shaft e are in such angular relation thereto that when they are alined with the slot d^5 in the depending flange d^2 , the knife blades i, i' are disengaged from their respective clips so that the switch is open. The tangential slots e' must be alined with the slot d^5 before the door d can be swung open. This insures that the switch must be opened before the door is opened for manipulation of the fuses. Contrariwise the door d must be closed before the switch is closed. The relation of parts described insures that when the cover b is to be removed from the box a the door d must first be opened since the detent c cannot be oscillated except when the lug d^3 is out of line with the lug c^2 . The practical effect of this relationship is that the cover b may not be removed except when the switch is open.

In order that the switch may be positively locked in opened position the handle e^2 may be provided with a strap r which has stamped therein a hole r' to receive a positive lock, such as s . The lock can be engaged with the hole r' only when the switch is open and the strap r is moved to a point where the hole is in front of the enlargement b^3 of the cover b . When the lock is thus engaged with the strap r it co-operates with the enlargement b^3 in such manner as to prevent the switch from being closed. In another condition it may be desired to lock the switch open and the door d closed. To permit this, the door d is provided with a lug d^6 with which may be alined, when the door is closed, a hole r^2 in the strap r , this alinement being possible only when the switch is open. A positive lock passing through the hole r^2 and the lug d^6 then serves to secure the switch in open position and the door d in closed position.

The hand operated latch p is provided in order that, if desired, the switch may be latched in open position from the inside of the box and the cover b then secured to the box to guard against surreptitious manipulation of the latch. When the switch is opened the tangential slots e^6 in the shaft e are brought into alinement with the restricted portion p^2 . If the latch b is then rocked on its pivot it will enter the tangential

slots e^6 and prevent further oscillation of the shaft e .

All of the parts described herein are of very simple and inexpensive construction, being made up for the most part as stampings. The assembling and disassembling of these parts has been greatly facilitated by their construction and relationship and the result is a substantial reduction in the total cost of manufacture. In assembling the shaft e with its squared portion e^5 is passed through the opening d^4 in the depending flange d^2 of the door d and through the side of the cover b . It will then slide through the insulating sleeve h on which are carried the knife blades i, i' . When the shaft e is home the blades i, i' may be slid along the sleeve h until alined with their respective clips when the set screw k may be tightened. Any one or more of the bases q, q', Q may be readily secured in place or removed for replacement or repair of any of the elements carried thereon by first removing the cover b , since the switch mechanism comes off with the cover. The retaining screws q^2, q^3 are accessible when the cover is thus removed.

While the preferred forms of all of the elements have been illustrated and described herein with some particularity it is to be understood that changes thereof within the skill of a mechanic may be made without departing from the invention and it is also to be understood that the invention is not to be avoided by the employment of less than all of the elements referred to.

I claim as my invention:

1. In combination with a line switch and fuses, a box in which they are supported, a cover for the box having an opening therein to give access to the fuse compartment, a door hinged on the cover and closing said opening, means carried with the door and co-operating with the switch to prevent opening of the door while the switch is closed and prevent closing of the switch when the door is open, a lug on the cover and a detent pivoted on the box provided with a lug to co-operate with the first named lug to hold the cover in place.

2. In combination with a line switch and fuses, a box in which they are supported, a cover for the box having an opening therein to give access to the fuse compartment, a door hinged on the cover and closing said opening, means carried with the door and co-operating with the switch to prevent opening of the door while the switch is closed and prevent closing of the switch when the door is open, a lug on the cover, a detent pivoted on the box and having a lug co-operating with the first named lug to hold the cover against removal, and means carried with said door to prevent movement of said detent when the door is closed.

3. In combination with a line switch and fuses, a box in which they are supported, a rock shaft for the switch journaled in the side walls of the box, and a latch for the rock shaft pivoted within the box and formed with an enlarged opening through which the rock shaft passes freely and with a constricted slot communicating with said opening, the rock shaft being formed with a tangential slot adapted to be aligned with said restricted slot when the switch is opened to permit the latch to be engaged with the shaft and hold it against oscillation.
4. In combination with a line switch and fuses, a box in which they are supported, said box having a removable cover, said cover being provided with an opening therein to give access to said fuses, a door hinged on the cover and closing said opening, holding means for said cover and means mounted upon said cover and co-operating with said switch and said holding means to prevent removal of said cover while said door is closed, the opening of said door while said switch is closed and the closing of said switch when said door is open.
5. In combination with a line switch and fuses, a box in which they are supported, said box having a removable cover, said cover having an opening therein to give access to said fuses, a door on said cover closing said opening, means carried by the door and co-operating with said switch to prevent opening of the door while the switch is closed and prevent the closing of the switch when the door is open, said cover and box being provided with detent means co-operating with said door to prevent the removal of said cover while said door is closed.
6. In combination with a line switch and fuses, a box in which they are supported, said box having a cover provided with a hinged door providing access to said fuses, a rock shaft for actuating said switch and a swinging detent for holding together said cover and door, said rock shaft, door and detent being provided with interlocking portions for preventing movement of said door except when said rock shaft is in a predetermined position and preventing operation of said detent except when said door is in a predetermined position.
7. In combination with a line switch and fuses, a box in which they are supported, said box having a cover provided with a hinged door providing access to said fuses, a rock shaft for actuating said switch and a swinging detent for holding together said cover and door, said rock shaft, door and detent being provided with interlocking portions for preventing operation of said rock shaft except when said door is in a predetermined position and preventing operation of said detent except when said door is in a predetermined position.
8. In combination with a line switch and fuses, a box in which they are supported, said box having a cover provided with a hinged door for controlling access to said fuses, a rock shaft for actuating said switch, said door being provided with an interlocking portion having an opening through which said rock shaft passes, said interlocking portion being provided with a constricted arcuate slot communicating with said opening, said rock shaft being provided with a tangential slot adapted to align with said arcuate slot when the switch is open to permit said door to be opened, said box and cover being provided with a detent for holding same closed, said interlocking portion and said detent having interlocking members whereby said detent is prevented from moving when said door is in a predetermined position.
9. In combination, a fuse box having fuse blocks and switch members mounted therein, said box being provided with a cover having a hinged door, said hinged door providing access to said fuse blocks, a rock shaft for co-operation with said switch members, said door being provided with an arcuate slot, said rock shaft being slotted to align with said arcuate slot whereby said door may be moved only when said rock shaft is in a predetermined position, said arcuate slot having communicating therewith an enlarged opening permitting free rotation of said rock shaft whereby when said door is closed said rock shaft may turn freely, said box and cover being provided with detent means for holding same together, said detent means being provided with locking means co-operating with said door whereby said detent means may be operated only when said door is in open position.
10. In combination with a line switch and fuses, a box in which they are supported, said box having a removable cover, said cover being provided with an opening there-in to give access to said fuses, a door hinged on the cover and closing said opening, holding means for said cover and means mounted upon said cover and co-operating with said switch and said holding means to prevent removal of said cover while said door is closed, the opening of said door while said switch is closed and the closing of said switch when said door is open, latch means being provided operating independently of said door for preventing the closing of said switch.
11. In combination with a line switch and fuses, a box in which they are supported, said box having a removable cover, said cover having an opening therein to give access to said fuses, a door on said cover closing said opening, means carried by the door and co-operating with said switch to prevent opening of the door while the switch is

- closed and prevent the closing of the switch when the door is open, said cover and box being provided with detent means co-operating with said door to prevent the removal of 5 said cover while said door is closed, latch means being provided operating independently of said door for preventing the closing of said switch.
12. In combination with a line switch and 10 fuses, a box in which they are supported, said box having a cover provided with a hinged door providing access to said fuses, a rock shaft for actuating said switch and a swinging detent for holding together said cover and door, said rock shaft, door and 15 detent being provided with interlocking portions for preventing operation of said rock shaft except when said door is in a predetermined position and preventing operation of said detent except when said door is in 20 a predetermined position, latch means being provided operating independently of said door for preventing operation of said rock shaft.

This specification signed the 4th day of 25 May, 1921.

POVL HARTMANN.
